GRINDER

Hans Petersen, Minneapolis, Minn., assignor to
 Storm Manufacturing Company, Inc., Minneapolis, Minn., a corporation of Minnesota

Application January 29, 1940, Serial No. 316,091

7 Claims. (Cl. 51—241)

This invention has relation to a grinder or grinding machine useful for a variety of purposes, but designed to be more especially useful to the purposes of grinding the connecting rod journals and the main journals of the crank shafts of automotive vehicles.

An object of the invention is to provide a grinding machine which will be of novel and improved construction.

A further object is to provide a grinding machine of the type herein presented wherein will be incorporated various improved features and characteristics of construction which will be novel both as individual entities of said grinding machine and in combination with each other.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limited sense, changes in details of construction and arrangement of parts being permissible so long as within the spirit of the invention and the scope of the claims which follow.

In the accompanying drawings forming a part of this specification,

Fig. 1 is a rear elevational view of a grinder including features and characteristics of the invention, disclosed as when applied to one of the uses to which said grinder can be put;

Fig. 2 is a side elevational view of the grinder as it would appear when viewed from the right hand side in Fig. 1;

Fig. 3 is an enlarged longitudinal sectional view, partially in elevation and partially broken away, taken substantially on line 3—3 in Fig. 1;

Fig. 4 is an enlarged fragmentary front elevational view of the grinder;

Fig. 5 is an enlarged sectional view, taken substantially as on line 5—5 in Fig. 2, with parts omitted in the interest of clarity;

Fig. 6 is an enlarged plan view of a gear box cover removed from the grinder, detailing gear elements or gearing associated with said cover and adapted to be housed by said gear box;

Fig. 7 is an enlarged fragmentary elevational view of the disclosure of Fig. 6 as said disclosure would appear when viewed from the top of the sheet;

Fig. 8 is a sectional view, taken on line 8—8 in Fig. 6, detailing a shifter rod of the gear shifter device of the grinding machine; and

Fig. 9 is a view corresponding generally with the disclosure of Fig. 8, but showing said shifter rod situated in a different position.

With respect to the drawings and the numerals of reference thereon, a frame for the grinder or grinding machine is denoted generally at 15. More explicitly, said frame 15 is of elongated configuration and is constituted as an elongated body portion 16 and an elongated extension portion 17 upon and integral with said body portion.

The body portion 16 of the frame 15 supports a bracket member 18 adapted to be adjusted longitudinally of said body portion and frame 15 in direction toward and away from said extension portion 17 of the frame. More explicitly, said bracket member 18 includes a base portion 19 thereof slidably movable over an adjacent surface 20 of the body portion 16 of the frame 15, and oppositely disposed flange portions 21, 21 thereof slidably movable over surfaces 22, 22 of said body portion 16 which are opposite said base portion 19 and said surface 20. Stated otherwise, the oppositely disposed flange portions 21, 21 are spaced from the base portion 19, as well as from each other, and extend inwardly in parallel relation to said base portion 19, to provide oppositely disposed guideways 23, 23 of the bracket member 18 extending longitudinally of the body portion 16 in which the opposite side edge portions 24, 24 of said body portion 16 are snugly, but slidably, situated. That is, the bracket member 18 is adapted to be adjusted lengthwise of the body portion 16 by slidable movement of said bracket member 18 and its oppositely disposed guideways 23, 23 along the opposite side edge portions 24, 24 of said body portion 16.

Mechanism is included for accomplishing sliding adjustment of the bracket member 18 along the body portion 16 of the frame 15, and for securing said bracket member at any position to which adjusted lengthwise of said body portion, at distance closer to or farther from the extension portion 17.

As disclosed, the bracket member 18 includes an integral arm 25 disposed perpendicularly to the base portion 19 of said bracket member and situated adjacent the end portion 26 of the body portion 16 of the frame 15 which is opposite the extension portion 17, in spaced relation to said end portion 26 and in alining relation to said body portion 16. An adjusting member or screw 27 is rotatably mounted and fixed against longitudinal movement, as indicated at 28, in the arm

25, and an end portion 29 of said adjusting screw 27 is threadably mounted, as at 30, in said end portion 26 of the body portion 16. A slot 31 in said body portion 16 at the side of the end portion 26 opposite the arm 25 provides clearance for longitudinal movement of the adjusting screw 27, as will be evident. Said adjusting screw 27 is arranged perpendicularly to said arm 25 and parallelly of, or in alignment with, the body portion 16, and the end portion of the adjusting screw 27 which is opposite the threaded end portion 29 fixedly supports a finger piece 32 through the instrumentality of which said adjusting screw can be rotated, thus to accomplish adjustment of the bracket member 18 longitudinally of the frame 15 and its body portion 16, toward and away from the extension portion 17. Clearly, by turning the adjusting screw 27 in one direction, it will be caused to move inwardly of the body portion 16, thus to cause the bracket member 18 to be adjusted in direction toward the extension portion 17, and by turning said adjusting screw in opposite direction, it will be caused to move outwardly of said body portion 16, thus to cause said bracket member 18 to be adjusted in direction away from said extension portion 17. Obviously, the bracket member 18 will be secured in fixed relation to the frame 15 at any location along the length of the body portion 16 of said frame to which said bracket member may be adjusted.

The base portion 19 of the bracket member 18 supports a carriage 33 adapted to be reciprocated upon said base portion in direction transversely of the frame 15 and its body portion 16 and perpendicular to the direction in which said bracket member 18 is adjustable along said body portion 16. That is, the carriage 33 is reciprocable in a plane which extends transversely of the body portion 16 and also is perpendicular to the plane in which the bracket member is adjustable along said body portion 16. More explicitly, said carriage 33 includes a base portion 34 thereof slidably movable over an adjacent surface 35 of the base portion 19 of said bracket member 18, and oppositely disposed, oblique or bevel flange portions 36, 36 thereof slidably movable over oblique bevel surfaces 37, 37 of said base portion 19 which are opposite said base portion 34 and said surface 35. Stated otherwise, the oppositely disposed, oblique or bevel flange portions 36, 36 are spaced from the base portion 34, as well as from each other, and extend inwardly in oblique or bevel relation to said base portion 34, to provide oppositely disposed guideways 38, 38 of the carriage 33 extending transversely of the body portion 16 in which the opposite, upper and lower as disclosed in Fig. 3, side edge portions 39, 39 of the base portion 19 of the bracket member 18 are snugly, but slidably situated. That is, the carriage 33 is adapted to be reciprocated transversely, or in sidewise direction, of the body portion 16 by slidable movement of said carriage 33 and its oppositely disposed guideways 38, 38 along the opposite side edge portions 39, 39 of said base portion 19 of the bracket member 18.

The carriage 33 supports, or includes, several, or a number of, parts of the grinding machine presently to be described, and mechanism is included for accomplishing reciprocation of said carriage, together with the parts supported, or included, thereby, upon the base portion 19 of said bracket member 18.

As disclosed, the carriage 33 rigidly supports

an electric motor 40 at the side of said carriage opposite the extension portion 17, and said electric motor includes a driven shaft 41 at the extension portion 17 side of the motor which extends through and across a gear box 42 of or provided by the carriage, in direction parallel with a part of the extension portion 17 and toward another part of said extension portion, as well as parallel with the body portion 16 of the frame 15. The motor shaft 41 includes an inner end portion thereof suitably and conveniently mounted, as at 43, within the gear box 42, an intermediate portion thereof suitably and conveniently mounted, as at 44, in a bearing member 45 supported by said gear box, and an outer end portion thereof, at the outer side of said bearing member 45, suitably and replaceably, fixedly supporting a grinding disc 46. The construction and arrangement is such that the motor shaft 41 and the grinding disc 46 thereon are rotatable relatively to the carriage 33 and the electric motor 40, but are fixed against other movement with respect to said carriage and electric motor, and during reciprocatory movement, as well as movement of adjustment, of the carriage 33, the electric motor 40, together with its shaft 41, the grinding disc 46 rigid with said shaft, and other parts supported by said carriage, moves with the carriage as a unit.

A worm 47 fixed upon the motor shaft 41 and situated within the gear box 42 meshes with a worm wheel 48 fixed upon a spindle 49 rotatably mounted in spaced bearings 50, 50 suitably fixed upon a cover 51 for the gear box 42. The cover 51 is removably fastened upon the gear box 42 by screw bolts 52. As shown, the worm wheel 48 is arranged between the bearings 50, 50, and an extension portion 53 of said spindle 49 fixedly supports a worm 54 which meshes with a gear 55 fixed upon a shaft 56 rotatably mounted in said cover 51. A pinion 57 is fixed upon said shaft 56 and is situated at the inner side of the gear 55.

A stub shaft 58, disposed perpendicularly to the cover 51, as well as to the body portion 16 of the frame 15, extends through the gear box 42. An outer or rearward end portion of said stub shaft 58 is rotatably mounted, as at 59, in said cover 51, and an inner or forward end portion of the stub shaft is rotatably mounted, as at 60, in a wall of the gear box 42 constituted as a part of the carriage 33. The outer or rearward end of the stub shaft 58 fixedly carries a hand piece 61, situated at the outside of said gear box 42, through the instrumentality of which said stub shaft can be manually rotated, and the inner or forward end of the stub shaft fixedly supports a crank 62 which also is situated at the outside of the gear box.

A gear 63 is splined, as at 64, to the stub shaft 58 to rotate with said stub shaft and to be movable longitudinally thereon, either to be brought into meshing relation with the pinion 57, or to be removed from engagement with said pinion.

A gear shifter device is for accomplishing longitudinal movement of the gear 63 upon said stub shaft 58, selectively to cause said gear 63 to be engaged with the pinion 57 or to be removed from engaging relation with said pinion. Said gear shifter device includes a shifter rod 65 which is mounted, as at 66, in the cover 51 for longitudinal sliding movement. Said shifter rod 65 fixedly supports a finger piece 67 upon its outer or rearward end to be manipulated to accom-

plish longitudinal adjustment of the shifter rod, and also fixedly supports a shifter arm 68 upon its inner or forward end. The shifter arm 68 includes a fork portion 69 thereof which lies between spaced annular elements 70, 70, upon the stub shaft 58 and rigid with the gear 63. The construction and arrangement is such that the annular elements 70, 70 are rotatable with the gear 63 and the stub shaft 58 when these are rotated, and relatively to the shifter arm 68 and its fork portion 69, as will be understood. It will be obvious that when the shifter rod 65 is in withdrawn position, as in full lines in Fig. 7, the gear 63 is in meshing relation to the pinion 57, and when said shifter rod is in inserted position, as in dotted lines in said Fig. 7, said gear 63 is removed from said pinion 57.

In Fig. 8 of the drawings the shifter rod 65 is disclosed positioned as in full lines in Fig. 7, with the pinion 57 and the gear 63 in interengaging relation. As shown in said Fig. 8, a ball 89 is resiliently pressed by a coil spring 90 into an annular slot 91 of said shifter rod to insure that said pinion 57 and gear 63 will not become accidentally disengaged. The construction and arrangement is such that the shifter rod readily can be slid or moved from its position as in Fig. 8 to its position as in Fig. 9 when this is intentional. In said Fig. 9 said shifter rod is disclosed positioned as in dotted lines in Fig. 7, with the pinion 57 and the gear 63 removed from each other, and the spring pressed ball 89 removed from the annular slot 91, above said annular slot.

The crank 62 is adjustably secured to one end portion 71 of a connector rod 72 which is freely situated within a clearance passageway 73 extending through the base portion 19 of the bracket member 18 in direction transversely of the body portion 16 of the frame 15. Said connector rod 72 projects beyond both ends of the clearance passageway 73, and is itself substantially perpendicular to said body portion 16, as well as disposed between and substantially parallel with the oppositely disposed guideways 38, 38. An end portion 74 of the connector rod 72 which is opposite said end portion 71 is pivotally secured, as at 75, to an outer portion 76 upon the base portion 19 at the side of said base portion opposite said crank 62.

The adjustable connection between the crank 62 and the end portion 71 of the connector rod 72 is of construction to provide for alteration of the effective radius or throw of said crank. More explicitly, the crank 62 is constituted as a channelled member having an annular flange 77 upon, perpendicular to and integral with an intermediate portion of the base thereof and rigidly secured upon the adjacent end of the stub shaft 58 in such manner that said annular flange 77 is in contiguous or adjacent relation to a part of the carriage 33. See Fig. 5. Said channelled member which constitutes said crank 62 additionally includes spaced apart, oppositely disposed, parallel side wall portions 78, 78 thereof integral with the base of said channelled member and disposed at the side of said base opposite the annular flange 77, as well as spaced apart, oppositely disposed, alining, inwardly extending flange portions 79, 79 thereof which are integral with the edge portions of said side wall portions 78, 78 opposite the base of the channelled member. The base, side wall portions 78, 78 and inwardly extending flange portions 79, 79 of said channelled member together provide an elongated guide slot 80 with-

in the channelled member, as well as an elongated guide slot 81 of said channelled member between the edges of the flange portions 79, 79, of width narrower than the elongated guide slot 80, and said flange portions 79, 79 provide longitudinally extending shoulders 82, 82 disposed at the side of the elongated guide slot 80 adjacent the elongated guide slot 81 and to the rear or back of said elongated guide slot 81. 5 A connector pin includes a head 83 thereof slidably situated within the elongated guide slot 80 in contiguous relation to the base, side wall portions 78, 78 and longitudinally extending shoulders 82, 82 of the channelled member, and 10 an elongated body portion 84 thereof situated within and extending outwardly beyond the elongated guide slot 81 in spaced relation to the inwardly extending flange portions 79, 79. A rectilinear block 85 is snugly arranged upon 15 the elongated body 84 of the connector pin, normally in engagement with the head 83 of said pin, to be movable longitudinally of the pin, and is slidably situated within the elongated guide slot 81 in contiguous relation to the adjacent edges of said inwardly extending flange portions 79, 79. A portion of the body 84 of the connector pin which is at the side of the block 85 opposite the head 83 is rotatably mounted, as at 86, in the end portion 71 of the connector rod 72, and a nut 87 upon the end of said body 84 opposite said head 83, assisted by washers 88, 88 upon the connector pin and between the connector rod and the block and the connector rod and the nut, respectively, retains the parts in proper assembled relation. Clearly, by loosening adjustment of the nut 87, the connector pin and the block can be adjustably slid to any desired position along the channelled member, closer to or farther from the axis for the stub shaft 58, thus to adjust the radius or throw of the crank 62, and by tightening adjustment of said nut 87, said connector pin and block can be securely locked at any position along said channelled member to which the connector pin and block may be adjusted in a particular instance. With adjustment of said connector pin and block in direction away from the axis for said stub shaft 58 the radius or throw of the crank is of course made greater, and vice versa.

Assuming the frame 15 to be supported in some manner, and the pinion 57 and the gear 63 to be interengaged, it will be evident that energization of the electric motor 40 will not only cause the motor shaft 41, and with it the grinding disc 46, to be rotated, but also will cause the carriage 33, and the parts supported or included by said carriage, to be reciprocated in direction transversely of the body portion 16 of said frame. That is, the carriage 33, the motor 40 with driven shaft 41 and grinding disc 46, etc., will be reciprocated along the base portion 19 of the bracket member 18 in response to rotation of the motor shaft through the instrumentality of the worm 47, the worm wheel 48, the spindle 49, the worm 54, the gear 55, the shaft 56, the pinion 57, the gear 63, the stub shaft 58, the crank 62, the connector pin and the connector rod 72. Obviously, rotational movement of said crank, produced by rotational movement of the stub shaft 58, will cause said stub shaft, with the carriage, etc., to be moved to and from, or reciprocated. More explicitly, movement of rotation imparted to the crank 62 will cause the stub shaft 58 and

the carriage 33, etc., to have tendency toward rotational movement, or movement in a circular path, about the connector pin and its axis 86 upon the connector rod 72, which rotational movement, or movement in a circular path, of course will be resisted because of the fact said carriage is mounted upon the bracket member 18 to be capable of having only reciprocatory movement. Instead, rotation of the crank 62 will cause the connector rod 72 to oscillate upon its axis 75, the elongated body 84 of the connector pin to rotate in its bearing at 86, and the stub shaft, carriage, etc., uniformly to be reciprocated, in direction longitudinally of the connector rod 72 and transversely of the body portion 16 of the frame 15, alternately toward and to either side of said connector pin, adjacent and opposite the pivotal connection 75. Evidently, when the gear 63 is removed from engagement with the pinion 57, the electric motor 40 will be rendered incapable of causing the carriage, etc., to be reciprocated or moved transversely of the body portion 16 of the frame 15. When the driving connection between the motor and crank 62 is broken, by disengagement of the pinion 57 and the gear 63, said crank can be rotated to cause the carriage to be moved transversely, or reciprocated, by manual rotation of the stub shaft 58 through the instrumentality of the hand piece 61 upon said stub shaft.

The extension portion 17 of the frame 15 is more especially for the purpose of associating the grinding machine with, or assembling said grinding machine upon, work to be performed. More explicitly, said extension portion 17 includes a straight length 92 thereof in adjacent relation to the body portion 16 of said frame 15, and a part-circular length 93 thereof at the end of said straight length 92 which is opposite or spaced from said body portion 16. The part-circular length 93 of the extension portion 17 provides an internal part-cylindrical surface 94 of said part-circular length 93 which is arranged in a circumference spaced a slight distance from the grinding disc 46, and the axis for the motor shaft 41 is disposed diametrically of said mentioned circumference. A part-circular element 95 pivoted, as at 96, upon the end portion of the part-circular length 93 which is opposite or spaced from the straight length 92 of said extension portion 17 provides an internal part-cylindrical surface 97 which in effect is adapted to constitute a continuation of said internal part-cylindrical surface 94. That is, the internal part-cylindrical surfaces 94 and 97 are adapted to lie in a single circumferential surface when the grinding machine is applied to work to be performed. A straight portion 98 of the part-circular element 95 which is opposite or spaced from the part-circular length 93 is spaced from and substantially parallel with the straight length 92 of the extension portion 17 when the grinding machine is applied to use, and the bearing member 45, the motor shaft 41 and the grinding disc 46 upon said motor shaft, are situated between and in spaced relation to said straight portion 98 and said straight length 92.

The part-circular length 93 supports each of a pair of spaced apart blocks 99 and 100 situated at and adjacent to the internal part-cylindrical surface 94, and the part-circular element 95 supports a block 101 situated at and adjacent to the internal part-cylindrical surface 97, between said part-circular element 95 and the straight por-

tion 98 as disclosed. The blocks 99, 100 and 101 are spaced at substantially 120 degrees apart, and said block 99 is spaced approximately 180 degrees from the grinding disc 46. Each of the blocks 99, 100 and 101 is imbedded in the member which supports the block, and is secured to said member in any suitable and convenient manner, as by a small screw bolt 102.

Each of the blocks 99, 100 and 101 supports a pair of aligned small shafts 103, including a shaft 103 mounted in the corresponding block at each side thereof and slidably adjustable inwardly and outwardly of said block. Means as disclosed for fastening each small shaft 103 at any position to which it may be adjusted in the corresponding block, either farther inwardly or farther outwardly of said block, is constituted as a locking screw 104 situated in the block and adapted to be turned into clamping engagement with the corresponding small shaft. The outer end of each small shaft 103 rotatably carries a roller 105, and the set of rollers 105 at each side, respectively, of the blocks 99, 100 and 101 are adapted to lie in a single circumferential or cylindrical surface which is normal to the motor shaft 41 and the grinding disc 46 fixed upon said motor shaft when the grinding machine is in operation upon a job to be performed. The outer, working surface of said grinding disc 46 lies at the circumferential or cylindrical surface in which the rollers 105 are situated. The outer end portion of each roller 105 is of reduced configuration as disclosed.

The sets of rollers 105 at the opposite sides, respectively, of the blocks 99, 100 and 101 are adapted to be supported upon, or engaged with, a member or journal, such as a connecting rod journal or a main journal of a crank shaft, to be ground, thus to cause the grinding disc 46 to be situated, or retained, in proper grinding relation to said member or journal. The part-circular element 95 is pivotally supported upon the part-circular length 93 of the extension portion 17 in order that the grinding machine readily and easily can be associated with or assembled upon, and removed from, a member or journal to be ground. Said part-circular element 95 is retained in relation to the part-circular length 93 so that all of the rollers 105 desirably will lie in a single circumferential or cylindrical surface normal to the grinding disc 46, when the grinding machine is in operation, through the instrumentality of a flat spring 106 having one of its ends secured, as at 107, to the end of the straight portion 98 opposite or spaced from the part-circular length 93 and its other end portion removably retained against movement in direction away from the straight length 92 by a hoop member 108 pivotally supported, as at 109, upon the frame 15. Said flat spring 106 includes a hook portion 110 thereof for detachably engaging said hoop member 108. Clearly, by disengagement of the hook portion 110 from the hoop member 108, the flat spring 106 and the part-circular element 95 and its straight portion 98 can be swung in direction away from the extension portion 17 to allow access to the space within the part-circular length 93 and adjacent the outer, working surface of the grinding disc 46, and by engagement of said hook portion 110 with said hoop member 108, the rollers 105 supported by the block 101 can be retained in the same circumferential or cylindrical surface which includes the rollers 105 supported by the blocks 99 and 100, which circumferential or cylindrical surface will be normal to the grinding disc 46.

A handle 111 for the grinding machine is, as disclosed, removably secured, as at 112, to the end portion 26 of the body portion 16 of the frame 15, which end portion is opposite or spaced from the extension portion 17.

In Fig. 1 of the drawings, the grinding machine is illustrated as when applied to the connecting rod journal 113 of a crank shaft 114 to cause said connecting rod journal to be ground. The grinding operation can be accomplished upon a connecting rod journal while the main journals 115 of the crank shaft are mounted in an automotive vehicle. Attention is called to the fact that not only are all of the rollers 105 engaged with the connecting rod journal 113 in Fig. 1, to support the grinding machine directly upon said connecting rod journal—as also shown in Figs. 2 and 3—but, also, in said Fig. 1 the rollers 105 of the opposite sets of rollers have been adjusted so that the outer ends or portions of said rollers are in engagement with the spaced apart crank arms 116, 116, respectively, at the opposite ends of and supporting the connecting rod journal, thus to fix the frame 15 against possibility of endwise or longitudinal movement relatively to the work or connecting rod journal during operation of the grinding machine. That is, the rollers 105 situate said frame 15 against the possibility of sidewise or transverse movement of the frame.

In Fig. 1 the connecting rod journal 113 may be rotated, as well as moved in a circular path, by rotation in any suitable and convenient manner of the crank shaft 114 upon its main journals 115. In such event, the frame 15 and all parts of the grinding machine, suspended or supported upon the connecting rod journal through the instrumentality of the rollers 105, will be moved to and fro, or upwardly and downwardly, and sidewise with the connecting rod journal as this is moved in a circular path about the main journals 115, and said connecting rod journal will, at the same time, be rotated relatively to said rollers 105 and the grinding disc 46. That is, the grinding machine will be moved to and fro and sidewise in response to movement in a circular path of the connecting rod journal 113, and said connecting rod journal also will be rotated within and relatively to the grinding machine. The handle 111 may be manually grasped, when this is preferred, during to and fro and sidewise movements imparted to the grinding machine by movement in a circular path of the connecting rod journal 113, thus to cause said grinding machine to be steadied.

The grinding machine can be employed to operate upon a member or journal other than a connecting rod journal such as 113, as, for example, a main journal such as 115. A crank shaft such as 114 having a main journal such as 115 to be ground or operated upon by the grinding machine herein presented will be removed from the automotive vehicle and suitably and conveniently mounted so that the main journal to be worked upon can be rotated. The grinding machine will be suspended or supported upon and fixed against endwise or longitudinal movement relatively to said main journal in the general manner as set forth in connection with the connecting rod journal 113, but a main journal being ground need merely be rotated in the grinding machine and relatively to the rollers 105 and the grinding disc 46, and not caused to be moved in a circular path as is a connecting rod journal operated upon while its crank shaft is mounted in an automotive vehicle.

The operation of the grinding machine itself is substantially the same when said machine is causing a connecting rod journal such as 113 to be ground as when the machine is causing a main journal such as 115 to be ground. In either instance, said grinding machine desirably is suspended or supported upon the journal being ground by rollers such as 105 which constitute work followers, locators and/or guides of or for the grinding machine. And, too, the rollers such as 105 additionally are employed to fix the frame such as 15 of the machine against movement endwise or longitudinally of the journal being worked upon and sidewise or transversely of said frame. In the instance of either a connecting rod journal or a main journal, or other member or journal, being operated upon, the grinding disc 46 is rotated and the carriage 33, with appurtenances, including said grinding disc, is reciprocated, in the manner as hereinbefore set forth, responsive to energization of the electric motor 40. The grinding disc while rotating, desirably at relatively high speed, is caused to be moved, or reciprocated, evenly and smoothly, and desirably slowly, endwise or longitudinally of the member or journal being ground, thus to operate upon said member or journal. Of course, the radius or throw of the crank 62 will be made such that the grinding disc 46 will operate upon a member or journal being ground throughout the whole of the length of the member or journal, or along any part of the length of said member or journal selected to be ground, as will be understood. Obviously, the adjusting screw or member 27 constitutes a feed screw or member of the grinding machine for situating the bracket member 18 and the carriage 33 with appurtenances closer to or farther from a member or journal being operated upon, thus to cause the disc 46 to be set at desired and predetermined grinding relation to said member or journal.

Preferably, the rollers 105 and the small shafts 103 which support said rollers will be removable from the blocks 99, 100, 101, to be replaceable by equivalent small shafts carrying equivalent rollers of larger or smaller diameter. That is, in the instance of journals of larger diameter to be ground, rollers such as 105 of smaller diameter desirably will be employed, and in the instance of journals of smaller diameter to be ground, rollers such as 105 of larger diameter desirably will be employed. Obviously, in every case the rollers 105 are adapted to cause a journal to be ground to be situated in exact perpendicular relation to the grinding disc so that the outer or grinding surface of said grinding disc will operate properly upon said journal.

The electric motor 40 can be energized by power from any suitable and convenient source (not shown). Lead wires 117 will extend to said electric motor from the source of power selected, and, as disclosed, a start and stop switch 118 for the electric motor is assembled with said lead wires at location conveniently close to the grinding machine.

What is claimed is:

1. In a machine for grinding a rotating journal, a frame, means for mounting said frame upon said journal, a bracket member mounted upon said frame for adjustment toward and away from said journal, a carriage mounted upon said bracket member for reciprocatory movement longitudinally of said journal, a motor rigid with said carriage, a motor shaft, a grinding entity rigid with said motor shaft and adapted to be opera-

tive upon said journal, means actuated by said motor shaft for causing said carriage to be reciprocated relatively to said bracket member, means for adjusting the length of the reciprocations of said carriage, and means for adjusting said bracket member with said carriage, motor, motor shaft and grinding entity toward and away from said journal.

2. In a machine for grinding a rotating journal, a support, means for mounting said support upon said journal, a carriage mounted upon said support for reciprocatory movement endwise of said journal, a motor rigid with said carriage, a motor shaft, a grinding entity rigid with said motor shaft and adapted to be operative upon said journal, means actuated by said motor shaft for causing said carriage to be reciprocated, and means for directing reciprocation of said carriage to a straight path.

3. In a machine for grinding a journal, a support, means for mounting said support upon said journal, a carriage mounted upon said support for reciprocatory movement longitudinally of the journal, means for directing reciprocation of said carriage to a straight path, a motor rigid with said carriage, a motor shaft, a grinding entity rigid with said motor shaft and adapted to be operative upon said journal, means actuated from said motor shaft for causing said carriage to be reciprocated, and means for adjusting said carriage with said grinding entity toward and away from said journal.

4. In a machine for grinding a journal, a frame, a bracket member mounted upon said frame for adjustment toward and away from said journal, a carriage mounted upon said bracket member for reciprocatory movement longitudinally of said journal, a motor rigid with said carriage, a shaft adapted to be rotated by said motor, a grinding entity adapted to be driven by said shaft and to be operative upon said journal, means operative in response to rotational movement imparted to said shaft by said motor for causing said carriage to be reciprocated relatively to said bracket member, means for directing reciprocation of said carriage to a straight path, and means for adjusting said bracket member with carriage in direction toward and away from said journal.

5. In a machine for grinding a journal, a sup-

port, a carriage mounted upon said support for reciprocatory movement longitudinally of said journal, a motor rigid with said carriage, a shaft adapted to be rotated by said motor, a grinding entity adapted to be driven by said shaft to be operative upon said journal, means operative in response to rotational movement of said shaft for causing said carriage to be reciprocated, means for directing reciprocation of said carriage to a straight path, and means for altering the length of the reciprocations of said carriage.

6. In a machine for grinding a rotating journal, a frame, means for mounting said frame upon said journal, a bracket member mounted upon said frame for adjustment toward and away from said journal, a carriage mounted upon said bracket member for reciprocatory movement longitudinally of said journal, a motor rigid with said carriage, a motor shaft, a grinding entity rigid with said motor shaft and adapted to be operative upon said journal, means actuated by said motor shaft for causing said carriage to be reciprocated relatively to said bracket member, means for directing reciprocation of said carriage to a straight path, and means for adjusting said bracket member with carriage, motor, motor shaft and grinding entity toward and away from said journal.

7. In a machine for grinding a rotating journal, a frame, means including spaced apart rollers for supporting said frame upon said journal, means for fixing the frame against endwise movement relatively to the journal, a bracket member mounted upon said frame for adjustment toward and away from said journal, a carriage mounted upon said bracket member for reciprocatory movement longitudinally of said journal, a motor rigid with said carriage, a shaft rigid with said carriage and adapted to be rotated by said motor, a grinding entity fixed upon said shaft and adapted to operation upon said journal, means actuated in response to rotational movement of said shaft for causing said carriage to be reciprocated, means for directing reciprocation of said carriage to a straight path, and means for adjusting said bracket member with said carriage, motor, shaft and grinding entity toward and away from said journal.

HANS PETERSEN.
